SAMUEL M. WILLIAMS, OF PINE VILLAGE, INDIANA.

Letters Patent No. 65,714, dated June 11, 1867.

IMPROVED EVAPORATOR.

The Schedule referred to in these Letters Patent and making part of the same.

TO ALL WHOM IT MAY CONCERN:

Be it known that I, SAMUEL M. WILLIAMS, of Pine Village, in the county of Warren, and State of Indiana, have invented a new and useful Improvement in Evaporator; and I do hereby declare that the following is a full, clear, and exact description thereof, which will enable others skilled in the art to make and use the same, reference being had to the accompanying drawings, forming part of this specification, in which—

Figure 1 is a top or plan view of my improved evaporator.

Figure 2 is a vertical longitudinal section of the same, taken through the line x x , fig. 1.

Figure 3 is a vertical longitudinal section of the same, taken through the line y y , fig. 1.

Figure 4 is a vertical cross-section of the same, taken through the line z z , fig. 1.

Similar letters of reference indicate like parts.

My invention has for its object to furnish an improved evaporator so constructed and arranged that the fire may be directed under either of the pans at pleasure, or may be shut off from either or all the pans, as may be desired; and it consists, first, in an improved evaporator formed by the combination of the pans with the furnace, when said furnace is constructed and arranged, as hereinafter more fully described; and, second, in the skimmer formed by the combination of the perforated plate, handle, and sliding-rod with each other, as hereinafter more fully described.

The furnace A consists of two rectangular boxes placed side by side and securely attached to each other, or of a single large box divided into two parts by a vertical longitudinal partition. The boxes are divided into two flues by the horizontal partitions a^1 and a^2 , the partition a^1 extending from the fire-chamber a^3 to the rear end of the furnace, and the partition a^2 extending the whole length of the furnace. a^4 is a damper pivoted to the sides of the furnace at the forward edge of the partition a^1 . When the damper a^4 is turned into the position shown in fig. 1, it closes the lower flue, and compels all the heat to pass through the upper one, and when it is turned up all the heat passes through the lower flue. In the rear part of the furnace an opening is cut through the interior side walls, and through the partitions a^1 and a^2 , as shown in figs. 2 and 4. This opening into the upper flue is closed on each side of the interior side walls of the furnace by the dampers a^5 and a^6 . The opening from the lower flue into the chimney B is closed by a damper, a^7 , and the opening from the upper flue into the chimney B is closed by a damper, a^8 . The pivoting-rods of all these dampers extend out through the side walls of the furnace and terminate in handles, so that the dampers may be readily operated. By means of these dampers the heat may be made to pass all the way from the fire-chamber to the chimney through the upper flue or through the lower flue, or part of the way through each, as may be desired. C is the pan into which the juice is first put, and in which it is kept till about one-third done. The pan C rests upon the side walls of the furnace. Its bottom forms the top of the upper flue, and it extends from the chimney to the rear end of the furnace. The sirup, when about one-third boiled down, is drawn off from the pan C into the pan D through the pipe c^1 . For convenience in doing this the pan D should be set at a little lower level than the pan C, as shown in fig. 4. The pan D rests upon the side walls of the furnace, and it is about two-thirds the size of the pan C. When the sirup is about two-thirds boiled down, it is drawn off through the pipe d^1 and put into the finishing-pan E. The finishing-pan E rests upon the side walls of the furnace directly over the fire-chamber, and it is divided into two parts by the horizontal partition e^1 . The lower part e^2 is kept partially filled with water, and the upper part e^3 contains the sirup to be boiled down. As the water in the part e^2 is vaporized, the steam passes off through the pipe e^4 coiled in the upper part e^3 of the pan. The pipe e^4 discharges the steam into the chimney B. By this arrangement it is impossible to scorch or burn the sirup while being finished, and when the operation is completed the sirup is drawn off through the pipe e^5 . F is the skimmer, the perforated or wire-gauze plate f^1 of which is pivoted to the cross-bar f^2 of the handle f^3 , as shown in figs. 1 and 3. To the forward side of the plate f^1 is pivoted the end of the sliding-rod f^4 . Upon the other end of the rod f^4 is formed an eye or loop which slides back and forth along the said handle, as the skimmer is operated. The ends of the cross-bar f^2 are of such a length that they slide along the upper edges of the pans and prevent the plate f^1 from descending so deep into the pans as to disturb the sediment. By means of this skimmer the scum is drawn to and up the inclined rear end of the pan C or D, and allowed to fall into the trough G or H by which it is carried out of the way.

I claim as new, and desire to secure by Letters Patent—

An improved evaporator formed by the combination of pans C, D, and E with the furnace A, when said furnace is constructed and arranged substantially as herein described and for the purposes set forth.

The skimmer F, formed by the combination of the perforated or wire-gauze plate f^1 , the handle f^3 , and the sliding-rod f^4 , substantially as described and for the purpose set forth.

SAMUEL M. WILLIAMS.
